DESIGN FOR AN ENVELOPE SEALER

Frederick K. Storm, Jr., Los Angeles, and Elmer H. Daniels, Pasadena, Calif., assignors to Hal-
don Manufacturing Co., Incorporated, Los An-
geles, Calif., a corporation of California

Application October 4, 1947, Serial No. 141,757

Term of patent 14 years

(Cl. D74—1)

To all whom it may concern:

Be it known that we, Frederick K. Storm, Jr., and Elmer H. Daniels, citizens of the United States, residing at Los Angeles and Pasadena, respectively, in the county of Los Angeles and State of California, have invented a new, original, and ornamental Design for an Envelope Sealer, of which the following is a specification, reference being had to the accompanying drawing, forming part thereof.

Figure 1 is a perspective view of an envelope sealer, showing our new design;

Figure 2 is a front elevational view of the device shown in Figure 1; and,

Figure 3 is a left end elevational view of the device shown in Figure 1.

We claim:

The ornamental design for an envelope sealer, substantially as shown.

FREDERICK K. STORM, JR.
